LINER PLATE

Anthony Foukal, Cleveland, Ohio, assignor to
Truscon Steel Company, Youngstown, Ohio, a
corporation of Michigan

Application June 24, 1936, Serial No. 87,090

7 Claims. (Cl. 61—45)

The present invention relates to tunnel liner plates, and more particularly to plates which are intended to be used in lining a tunnel built by the shield method, in which a shield is driven through the ground, and a lining is built up inside of the shield and in the rear of its cutting edge. It is common practice in the building of such tunnels, to drive the shield forward through the earth by hydraulic jacks, and to use the already constructed portion of the lining as a bearing member, against which the rear portions of the jacks thrust as they force the shield ahead.

In order to withstand this pressure exerted by the jacks, various structures of I-beams, etc. have been resorted to to reenforce the lining and bear the thrust.

One object of the present invention is to provide a plate having novel reenforcing means, whereby a lining constructed of such plates will withstand thrust of the jacks, and in which there will be a continuity of thrust resisting elements from the forward portion of the lining where the thrust is exerted rearwardly through the entire length of the lining.

Another object is to provide a plate in which the reenforcing means do not interfere with the joining and securing together of adjacent plates.

These objects are attained in a simple and relatively inexpensive manner by the structure disclosed in the accompanying drawings, in which:

Figure 1 is an end elevation of a section of a tunnel lining made up of the plates.

Figure 2 is a sectional view on the line 2—2 of Figure 1.

Figure 3 is a sectional view on the line 3—3 of Figure 1.

Figure 4 is a sectional view on the line 4—4 of Figure 3.

Figure 5 is a perspective view of one embodiment of the invention.

Figure 6 is a detail view showing means for securing adjacent plates.

Figure 7 is a sectional view showing a modification.

Figure 8 is a sectional view on the line 8—8 of Figure 7.

Figure 9 is a perspective view of the modified form of plate.

Figure 10 is a plan view of a section of tunnel lining built in the form of plate shown in Figures 1—6 inclusive.

Figure 11 is a similar view showing a section of a lining constructed of plates of the form shown in Figures 7 to 9 inclusive.

Figures 12, 14 and 16 are sectional elevations showing various modified forms of plate.

Figures 13, 15 and 17 are sectional views taken on the lines 13—13, 15—15 and 17—17 of Figures 12, 14 and 16, respectively.

Describing the drawings more particularly, and referring to Figure 1, a section of tunnel lining is shown made up of a plurality of plates designated 10. In order to clearly identify the margins of the plates, the edges which are toward the front or rear of the tunnel are designated as "sides", while those parallel to the axis of the tunnel are called "ends". Each plate 10 is composed of a skin plate 11 which forms the outer side of the lining, and which is preferably curved in a circumferential direction. At each side of the plate 11 there is an inwardly extending flange 12 which is preferably curved to conform to the curvature of the plate 11. Each end of the plate 11 is provided with an inwardly extending flange 13 which is preferably of somewhat less depth than are the flanges 12. The flanges 12 and 13 are provided with suitable bolt-receiving openings 14 for the reception of bolts 15 or other suitable securing means for holding the plates in assembled relation.

In order that the individual plates as well as the complete lining may resist the longitudinal thrust exerted by the hydraulic jacks in forcing the shield ahead through the earth, a thrust member is assembled with each plate 10. This thrust member is in the form of a corrugated plate 16 that is curved to conform to the curvature of the plate 11. The corrugations 17 extend from side to side of the plate 16, or in the direction of the thrust exerted by the shield moving jacks, and the edges of the plate 16 are in abutting relation with the side flanges 12 of the plate 10. The inner apices of the corrugations 17 are preferably in abutting relation with the inner surface of the plate 11. The plates 16 may be secured to the plates 10 in any suitable manner, for example, by welding, as at 18, the ends of the corrugated plate to the flanges 12.

In order to properly fasten the ends of adjacent plates together, supplemental securing means may be supplied. Thus additional plates 19 are illustrated as welded to the inner surfaces of the flanges 12 of adjacent plates, and overlying the flanges 13, the plates 19 bridging the flanges 13 and the joints between them. A convenient form is illustrated in Figures 5 and 6, where the supplemental plates 19 are shown as welded to the flanges 12 at one side of a plate, the intention being that these plates may be welded to

the flanges 12 of the next adjacent plate in the field, and after the plates have been assembled in place. The supplemental plate may be welded to the flanges of both plates after assembly.

5 The extended flanges 12, besides performing the function of bolting flanges are intended to obviate the necessity of disposing circular I-beams between longitudinally adjacent sections of the lining as has heretofore been practiced in 10 tunnel lining structures. The purpose of these extended flanges is to bear the circumferential load upon the tunnel lining which has heretofore been generally borne by I-beams or other structural members.

15 In Figures 7 to 9 inclusive a modification is shown in which structural members for supporting the circumferential load upon the lining are provided. In this structure the skin plate 20 is provided with side flanges 21 which may be of 20 substantially the same height as the end flanges 22 and both the flanges 21 and 22 may be substantially equal in height to the corrugations of 25 the thrust plate 23. In this form the supplemental plates, as 19 of the previously described 30 embodiment, are unnecessary inasmuch as the structural members 24, besides bearing the circumferential load, rigidly position the plates with 35 respect to one another.

The side flanges 21 are provided with bolt 30 openings 25 which, for convenience of access, are located in the open corrugations of the plate 23. The bolt openings 25 are suitably spaced to register with bolt openings 26 in the structural members. The end flanges 22 are provided with bolt 35 holes 27 for the fastening together of laterally adjacent sections.

The liner plates may be made of any suitable material, such as steel, or any suitable corrosion resisting or other alloy. The modification shown 40 in Figures 7 to 9 may be used with any sort of suitable reinforcing structure or shape instead of the illustrated structural members 24.

Preferably the liner plates 11 will be manufactured with sharp corners as at 28, in order 45 that they may be joined together in a structure having a substantially imperforate outer surface. Such a structure is desirable when for any reason a tunnel is not to be provided with some type of inner lining, as illustrated at 29 in Figure 1. The 50 sharp cornered plates may be fabricated by forming the side flanges 12 integrally with the skin plates, it being necessary only that the flanges be parallel in order to provide a tight joint between longitudinally adjacent plates. The end flanges 55 13 may be welded in position between the side flanges and are preferably welded continuously along each edge at the abutting portion of the plate or flange.

The modified plate illustrated in Figure 4 does 60 not have separate thrust and skin plates. In this form of plate the corrugated thrust resisting member 35 performs also the function of the skin plate, namely, that of holding the earth out of the tunnel. The plate 35 is mounted between 65 two side flanges 36 that are welded to its sides and flanges 37 are welded to its ends.

This modification is suitable for use in the 70 construction of tunnels where it is not necessary to leave surface conditions above the tunnel undisturbed. After the shield has moved beyond the lining the earth will settle and pack into the corrugations on the outside of the lining, and it will be readily seen that such settling might cause 75 a change in the surface of the ground, which

would be undesirable, for example, in tunneling beneath city streets.

The modifications of Figures 14 and 16 simply disclose the different methods in which the flanges may be secured to a skin plate. In Figures 14 and 15 the skin plate 37 is between the top portions of the plates 38 that form the side flanges, while in the modification of Figures 16 and 17, the sides of the skin plate 39 overlie the one edge of each of the side plates 40 that act 10 as flanges.

By referring to Figures 10 and 11 and 1 and 2 the advantages of a lining built of plates supplied with the corrugated reinforcing members of this invention will be apparent. It is advantageous 15 in tunnel lining practice to stagger the joints of plates forming successive courses, and by providing the plates with reinforcing members that extend continuously throughout the length of each, the joints may be staggered, while the lining will be reinforced against distortion due to the thrust at all points and a continuous thrust-resisting structure will be established from the forward end of the lining straight back through 20 the tunnel.

It will be appreciated that the corrugations of the plates of successive courses need not register. The extended area which the sides of the corrugated plates cover gives bearings of such large 25 extent that thrust is transmitted from one corrugated plate to the others regardless of the registration of the corrugations.

From the foregoing, it is thought that the construction, operation and many advantages of the herein described invention will be apparent to 30 those skilled in the art without further description, and it will be understood that various changes in the size, shape, proportion and minor details may be resorted to without departing from the spirit or sacrificing any of the advantages of 35 the invention.

What I claim is:

1. In a liner plate for tunnels including a skin plate having forward and rear sides, and flanges along the said sides, a corrugated thrust plate positioned between the flanges the ends of the corrugations at its edges being in abutting relation with the inner sides of the flanges. 45

2. In a liner plate for tunnels including a skin plate having flanges along its forward and rear edges, a corrugated thrust plate positioned between the flanges and adjacent and underlying the skin plate, the apices of the corrugations of one side of the thrust plate being in abutting relation with the adjacent surface of the skin plate, 50 and the opposite ends of the corrugations abutting against the respective flanges.

3. A liner plate for tunnels, comprising a skin plate curved to conform to the circumferential curve of a tunnel and having bolting flanges 60 at each end, and load bearing flanges at each side, and a thrust plate positioned between the flanges and having edges in abutting relation with the sides of the load bearing flanges, the said thrust plate having corrugations substantially parallel 65 to the axis of the curve of the skin plate and extending between the edges that are in abutting relation with the said load bearing flanges.

4. A liner plate for tunnels comprising a curved skin plate having curved bolting flanges along its 70 curved sides and bolting flanges of substantially the same depth along its ends, and a corrugated thrust plate mounted between the flanges and having its edges in abutting relation with the curved flanges, the thrust plate being curved to 75

conform to the curve of the skin plate and the corrugations of the said plate being substantially equal in height to the flanges, and substantially parallel to the axis of the curve of the plates.

5. A liner plate for tunnels comprising a skin plate, flanges at opposite edges of the skin plate, a thrust plate having both inwardly and outwardly extending corrugations of substantially the same height as the flanges, the thrust plate
10 being located between the flanges and with the edges abutting the sides of the flanges, the corrugations of the thrust plate being disposed substantially at right angles to the flanges, and the said flanges having bolt holes located between
15 adjacent outwardly extending corrugations and between the walls of inwardly extending corrugations.

6. A lining for tunnels including a plurality of

liner plates arranged in side by side relation in axially abutting circumferential courses, the said liner plates including thrust plates having longitudinal corrugations disposed substantially parallel to the axis of the tunnel and a circumferential load bearing structural member interposed between and abutting the ends of the corrugations of the plates in the adjacent successive courses.

5
10
15
7. A liner plate for tunnels comprising a plate having a forward edge and a rear edge, and corrugations extending longitudinally across the plate from the forward to the rear edge, and flanges secured respectively to the forward and rear edges of the plate, the sides of the respective flanges overlying and abutting the ends of the corrugations of the plate.

ANTHONY FOUKAL.
